UNITED STATES PATENT OFFICE.

GEORGE HOWLETT DAVIS, OF NEWARK, NEW JERSEY.

RESILIENT TUBE SOCKET.

Application filed January 8, 1926. Serial No. 80,085.

This invention relates to sockets or holders for thermionic vacuum tubes such as are employed in radio work.

The present invention, in some of its aspects, may be considered as an improvement upon that covered by my co-pending application, Serial No. 54,522, filed September 4, 1925. The general objects of the invention are, therefore, the same as in the previous case.

Among the special objects of the present invention are to provide improved means for resiliently supporting the socket upon a base or panel so as to protect the tube from shock or mechanical vibration, to combine such resilient supporting means with the contact strips of my prior application in such manner that both may be secured by the same fastening device, and to provide means for preventing angular displacement of such strips and supporting means.

In order that the invention may be readily understood, reference is had to the accompanying drawing forming part of this specification, and in which:

Figure 1 is a vertical central section through one of my improved resilient sockets complete, showing it as it appears when attached to a base or panel;

Figure 2 is a plan view thereof;

Figure 3 is an inverted plan view thereof;

Figure 4 is a view, showing in side elevation a modified construction of contact strip and supporting means;

Figure 5 is a fragmentary sectional view, similar to Fig. 1, but showing a further modified construction of contact strip and supporting means;

Figure 6 is a plan view of the combined contact strip and supporting means shown in Figure 5;

Figure 7 is an end view of the device shown in Figure 6; and

Figure 8 is a view similar to Figure 5, but showing a still further modified construction.

Referring to the drawings in detail, my improved socket comprises a shell 1, preferably formed by molding thermoplastic insulating materials such as phenol-formaldehyde condensation products, hard rubber compositions or the like. This shell is pref-

erably of frusto-conical shape, and is generally similar to that shown in my prior co-pending application. The upper or smaller end 2 is provided with a sunken center 3, in which are formed two small and two large holes 4 and 4^a respectively, to receive the contact pins projecting from the tube base. Inside of the shell are secured metallic contact strips 7, having their upper ends so positioned as to engage with a wiping contact the sides of the tube pins as the latter are inserted in the holes 4 and 4^a. These contact strips are held against the inner wall 60 of the shell, by means of screws 8, constituting binding posts, and carrying on their outer ends nuts 9, all as set forth in my prior application.

The shell of the present invention differs 70 from my prior design, however, in the following respects. At the center of the shell, is formed a pocket or cup 6, having a central opening 6^a for a purpose which will herein-after appear. In order to prevent the contact strips 7 from angular displacement about the screws 8, I form on the inside of the shell adjacent the holes through which the screws 8 pass, pairs of space lugs or ribs, as clearly shown at 1^a in Figure 3, these 80 ribs being so disposed as to snugly receive the strips 7 between them and thus securely maintain such strips in the proper position. (On account of clearness, these ribs have been omitted from Figure 1.)

X represents a suitable base or panel of insulating material on which the socket or holder is mounted. While in my prior application the edge 5 of the large end of the socket is shown as resting directly against such base or panel, in the present case, the edge 5 is spaced from the base or panel X by means of special resilient supporting means. Such supporting means, as shown in Figure 1, consists of resilient spring metal 95 clips 10 secured inside the shell and having their lower ends projecting beyond the edge 5 and bent to form suitable feet. One such clip or foot is provided for each contact strip 7, and the clip or foot is held in position by the same screw 8 which secures the corresponding contact strip 7, the clip 10 being shown as superposed upon the contact strip.

It will be understood that the ribs 1^a, shown in Figure 3, are preferably of such depth as to engage the sides of the clips 10, also, and thus prevent angular displacement of such clips.

A screw 11 is used to secure the socket to the base or panel, such screw passing through the hole 6^a in the bottom of the pocket or cup 6, and having a head which fits within such pocket. Between the head of the screw and the bottom of the pocket is interposed a helical spring 12, which serves to yieldingly hold the socket against the panel.

From the above description, it will be seen that the socket or shell 1 is confined between two separate resilient supporting means, namely, the spring feet 10 and the spring 12, which presses such feet against the panel. That is to say, the socket is resiliently supported in both directions, and in this way, the tube, when mounted in the socket, is effectively protected against shocks, jars or mechanical vibration.

Instead of forming the contact strips 7 and feet 10 separately, I may, if desired, form them from a single piece of resilient metal, as shown in Figure 4. In this figure, I have illustrated a spring clip 13, having its upper end bent over to form a contact 7' and having its lower end bent to form a resilient foot or support 10'. Such a clip would, of course, lie between the ribs 1^a, shown in Figure 3, and thus be securely held in position. This makes a very simple construction.

If it is not desired to use binding posts such as 9, shown in Figures 1, 2 and 3, I may employ the construction illustrated in Figures 5, 6 and 7. In these figures, I have shown how a spring clip constituting a contact 7' and a resilient foot 10' may be secured to the shell 1 by means of a small screw 14, terminating substantially flush with the outer surface of the shell, and may have its lower end extended as at 15 to support a binding screw 16. This screw may be provided with a pair of clamping nuts 17, between which the wire or lead may be secured. Also, as shown in Figures 5, 6 and 7, the clip is still further extended beyond the clamping screw 16, and has its end portion bent up to form a trough shape receptacle 18 of wire. The wire may be laid in this trough and then secured to the binding screw 16, or, if preferred, the binding screw 55 may be omitted and the wire soldered in the trough 18.

In Figure 8, I have illustrated a still further modified construction. Here, the contact strip 19, which is secured to the shell by a screw 21, having a nut 22, is extended horizontally, as shown at 20, and does not directly engage the panel X, but is received in a notch 1^b formed in the lower edge of the shell. The horizontal extension 20 carries, at 65 its free end, beyond the shell, a screw 24

having a head 23 which rests against the panel and constitutes a supporting foot. A binding nut 25, and lock nut 26, are fitted on the upper end of the screw 24, and constitute means for attaching the wire.

Other modified constructions and arrangements will readily suggest themselves to those skilled in the art, and may be employed without departing from the spirit of the invention. It will be seen that I have provided a socket which is simple and cheap to manufacture, attractive in appearance, and which will effectively protect the tube from shock and vibration and it is thought that the many advantages of my invention will be readily appreciated without further discussion.

What I claim is:—

1. A tube socket comprising a hollow shell of frusto-conical form, the smaller end being formed to receive a tube, and a plurality of springy strips mounted against the inclined inner wall of said shell, the free ends of said strips projecting radially beyond the edge of the larger end thereof and being bent to form resilient feet for supporting the socket.

2. A tube socket comprising a hollow shell, a plurality of resilient strips mounted within said shell and projecting radially beyond the edge thereof to provide a yieldable support for the socket, the projecting ends being free, and means independent of said strips for yieldingly pressing the said free ends against a fixed base.

3. The combination with a radio tube socket, of resilient supporting feet fixed thereto at one side thereof, and separate resilient means engaging the other side thereof for yieldingly holding the socket in position.

4. A radio tube socket comprising a hollow shell, resilient supporting means carried by and projecting from one side thereof and adapted to freely rest upon a base, a pocket at the other side of said shell, a spring in said pocket, and means bearing upon said spring and adapted to engage said base to yieldingly hold the socket in position.

5. The combination with a tube socket, of spring strips carried by and projecting radially therefrom, the projecting portions of said strips constituting means by which the socket is resiliently supported upon a suitable base, and a single central securing means holding the socket to the base, whereby said socket and resilient supporting means may be angularly adjusted on said base about said central securing means.

6. A tube socket comprising an insulating shell having holes for the reception of the prongs of a tube, contact strips of spring metal secured to the shell beneath said holes in such position as to be engaged by said prongs when inserted in the holes, the ends of said contact strips being extended radially beyond the shell to form means for resilient

ly supporting the socket upon a suitable base, and wiring terminals carried by the outer end portions of said strips, said wiring terminals being freely movable relative to said

5 base.

7. A tube socket comprising a hollow insulating shell, a plurality of metallic con-

tact strips inside of said shell, and means for securing said strips to the shell, the ends of said contact strips being extended radially 10 beyond the edge of the shell to form resilient feet on which the socket is supported.

In testimony whereof I affix my signature.

GEORGE HOWLETT DAVIS.
